UNITED STATES PATENT OFFICE.

MAHLON E. LAYNE, OF HOUSTON, TEXAS, AND SAMUEL N. HALL, OF SOUTH PASADENA, CALIFORNIA, ASSIGNOR TO LAYNE & BOWLER CORPORATION, OF LOS ANGELES, CALIFORNIA, A CORPORATION OF CALIFORNIA.

MEANS FOR FACILITATING THE REMOVAL OR DISASSEMBLING OF ROTARY PUMP MECHANISM.

Application filed June 23, 1924. Serial No. 721,746.

To all whom it may concern:

Be it known that we, MAHLON E. LAYNE, a citizen of the United States, residing at Houston, in the county of Harris and State of Texas, and SAMUEL N. HALL, a citizen of the United States, residing at South Pasadena, in the county of Los Angeles and State of California, have invented a new and useful Means for Facilitating the Removal or Disassembling of Rotary Pump Mechanism, of which the following is a specification.

This invention relates to the art of rotary pumping mechanism and refers particularly to certain modifications in the mechanism whereby a novel method of disconnecting certain parts of the same may be employed, and also to the method of disconnecting the parts.

After a rotary pumping mechanism has been assembled in position for elevating liquid from a well, such as a water well, and it has been desired to disconnect the stub shaft of the motor or other means employed for driving the well from the pump shaft of the mechanism, this operation performed in the customary manner has been extremely difficult and expensive.

This invention has for its primary objects to provide a simple method for assembling and disconnecting certain parts of the rotary pump mechanism, and to provide a pump mechanism in which such method of assembling and disconnecting the parts may be readily employed.

The various further objects and advantages of the invention will be readily apparent from a description of a preferred form of rotary pump mechanism embodying the invention and of the method of assembling and disconnecting the parts therefrom.

Reference is made to the accompanying drawings illustrating a rotary pump mechanism and method of disassembling the same, in which:

Figure 1 is an elevation of the mechanism, partially in vertical section.

Fig. 2 is a similar elevation of the upper part of the mechanism, likewise partially in vertical section, showing the mechanism in the process of assembling or disconnection.

Referring to the drawings, the rotary pumping mechanism embodies a pump 1 adapted to be suspended in a well by its discharge casing 2 which extends vertically from the pump to the top of the well and there terminates in a casing head 3, which connects with a line 4 into which the fluid of the well is discharged. The pump 1 is of the customary impeller-actuated type having one or more impellers 5 keyed to a sectional pump shaft 6 which extends vertically from the bottom up to the top of the well and is there connected to a stub shaft 7 of an electrical motor 8 or other driving means; the pump shaft 6 being located concentrically within the discharge casing 2 and enclosed by a shaft casing 9, likewise preferably in section, which provides bearing blocks 10 engaging the shaft 6 at intervals between the pump and casing head 3.

In addition to the opening communicating with the line 4, the casing head 3 is provided with an additional opening 10', normally closed by a plug 11 or other means, which opening 10' is preferably on the opposed side of the casing head 3 to which the line 4 connects, and located about the center of the casing head 3.

The motor 8 or other driving member is preferably supported on the casing head 3 by a stand 12, thus being spaced somewhat above the top of the casing head 3. The upper section of the shaft casing 9 terminates within or closely adjacent to the casing head 3 and there connects with a packing box 13 which also provides a cap or closure for part of the upper side of the casing head 3; the packing box 13 having an annular flange 14 at its upper end by which the box 13 is supported upon the casing head 3. The packing box 13 is threaded to the exterior of the upper section of shaft casing 9, as

indicated at 15, and is provided with a chamber 16 adjacent thereto. Above the chamber 16 the packing box 13 serves to support packing material 17 surrounding the stub shaft 7 of the driving member 8, which packing material is pressed downward within the packing box by a stuffing gland 18 threaded thereto.

19 indicates an oil duct extending vertically through the box 13 which is connected to a lubricant feed cup 20 which may be employed for feeding oil down through the box 13 so that the oil may flow down the shaft casing in order to lubricate the bearing blocks 10 thereof. A second oil duct 21 communicates with the center of the packing material 17 and may be fed with lubricant through the line 22.

The stub shaft 7 and pump shaft 6 of the mechanism are of such length that they couple together at a point within the casing head 3, a coupling 23 being employed for this purpose, which coupling preferably has its upper end extending above the top of the upper section of shaft casing 9 and is provided with one or more notches or other similar means 24 on its upper face by which engagement may be made with a wrench for the purpose herein-after described. Between the face and ends of the stub shaft 7 and pump shaft 6 of the mechanism there is placed on a spacer 25, of the requisite thickness, so that when the shafts 7 and 6 are forced thereagainst, the impellers 5 in the pump 1 will be properly centered within the pump mechanism, such spacers 25 preferably being provided with a threaded opening 26.

27 indicates a lug extending outward from near the upper end of the shaft casing 9, which lug is adapted to be brought in engagement with a stop 30 fixed to the discharge casing 2 to prevent the shaft casing 9 from turning during certain disassembling operations on the pump mechanism.

With a rotary pump mechanism as herein described, the motor or other driving member 8 may readily be disconnected by removing the plug 11 in the casing head 3; also removing the oil line 22 and feed cup 20 and associated parts from the upper end of the packing box 13. The packing box 13 is then readily disconnected or screwed upward from the upper section of the shaft casing, the lug 27 and stop 30 preventing improper rotation of the shaft casing during its disconnecting step. The packing box is then pushed further upward along the stub shaft 7 of the motor and held up by any suitable means, such as a prop 31 placed with one end resting upon the top of the casing head 3 and the other supporting the box 13 from its annular flanges 14.

In this position, the coupling 23 between the pump shaft 6 and stub shaft 7 is held by a

wrench 32 and the drive shaft 7 then reversed to break connections with the coupling. The stand 12 and motor 8 then may be removed if desired.

It is thus seen that we have provided a simple manner of assembling and disassembling certain parts of the pump apparatus. This assembling and disassembling of the apparatus is frequently necessary to properly center or align the impellers 5 in the pump 1, such aligning being determined by the thickness of the spacer 25 employed between the stub shaft 7 and the pump shaft 6. The threaded aperture 26 permits bolts or other devices to make engagement with the washer in removing the spacer 25 from the coupling 23 when it is desired to replace such spacer with a spacer of different thickness.

While the method and means herein described are well suited for the purposes of this invention, the invention is not limited to details of the method or mechanism herein set forth, but is of the scope set forth in the appended claims.

We claim:

1. In a deep well rotary pump mechanism, the combination of a rotary pump, a discharge casing suspending the pump and extending vertically, a pump shaft extending vertically from the pump and within the discharge casing, a casing enclosing the pump shaft, a discharge head connected to the upper end of the discharge casing, an electric motor mounted upon the casing head and having a motor shaft axially aligned with the pump shaft, means connecting the motor shaft to the pump shaft, said means being disposed within the discharge head, a detachable packing box connected to the upper end of the shaft-enclosing casing and forming a cap for the discharge head, said packing box being upwardly movable to permit the coupling of the pump shaft and motor shaft, the casing head being provided with a wrench-admitting opening.

2. In a deep well rotary pumping mechanism, the combination with a rotary pump having a vertically extending pump shaft, a shaft casing enclosing the pump shaft, a discharge casing enclosing the shaft casing, a casing head connected to the upper end of the discharge casing and provided with a wrench-admitting opening, a packing box connected to the shaft-enclosing casing and forming a cap for the discharge casing, an electric motor mounted on the discharge casing and having a stub shaft extending within the discharge casing, a coupling for connecting said motor shaft and pump shaft, said coupling being provided with wrench-engaging notches.

3. A rotary pump mechanism comprising a rotary pump, a pump shaft extending vertically, a casing enclosing the pump shaft,

a discharge casing for the pump enclosing the first mentioned casing, a casing head connected to the discharge casing, a packing box screwed to the exterior of the shaft-
5 enclosing casing at a point within the casing head, said packing box providing a cap for the casing head, said casing head having a wrench-admitting opening, an electric motor mounted on the discharge head and hav-

ing a stub shaft extending into the discharge 16 casing adjacent the lower end of the packing box, and a coupling connecting said stub shaft to said pump shaft.

Signed at Los Angeles, Calif., this 10th day of June, 1924.

MAHLON E. LAYNE.
SAMUEL N. HALL.
